UNITED STATES PATENT OFFICE.

HENRY A. WISE WOOD, OF NEW YORK, N. Y., ASSIGNOR, BY MESNE ASSIGNMENTS, TO WOOD NEWSPAPER MACHINERY CORPORATION, OF NEW YORK, N. Y., A CORPORATION OF VIRGINIA.

MACHINE FOR FINISHING AND COOLING STEREOTYPE PRINTING-PLATES.

1,238,973.

Specification of Letters Patent. Patented Sept. 4, 1917.

Application filed June 25, 1912, Serial No. 705,782. Renewed January 31, 1917. Serial No. 145,816.

To all whom it may concern:

Be it known that I, HENRY A. WISE WOOD, a citizen of the United States, residing at New York, in the county of New York and State of New York, have invented a new and useful Machine for Finishing and Cooling Stereotype Printing-Plates, of which the following is a specification.

This invention relates to the shaving, finishing and cooling of curved stereotype printing plates and the cutting of tails therefrom and it is designed to be embodied in machines particularly to be used in connection with any desired kind of the so-called hand casting boxes.

The principal objects of the invention are to provide an efficient, convenient and compact form of run-way for receiving the plates and feeding them forward through the various operating devices; to so construct this run-way that it of itself acts to control the feed of the plates therealong; to provide a simplified and improved arrangement for operating the devices for controlling the movement of the plate through the arch and into the cooling device; to provide an improved tail cutter adapted to cut the tail from the inside so as to leave the plate with the proper bevel thereon and remove a minimum of metal; to provide an improved mechanism for operating the tail cutter in an accurate path; to provide means whereby the severed tail will be prevented from passing along down the run-way with the plate and will be left in a convenient position to be removed from the machine by hand; to provide an improved construction of side shaving tool of such a character as to trim off the sharp edges of the plate which have been a source of trouble heretofore; to provide a construction suitable for operation by an electric motor, and automatic controlling connections therefor; to provide means in the cooling mechanism whereby it is adapted to receive a plate by gravity from the inclined run-way and gradually stop its motion without subjecting it to any sudden shock; to provide automatic means for turning on the cooling fluid by the operation of the plate itself when it moves into position in the cooling device, and to improve the details of construction in many particulars.

Reference is to be had to the accompanying drawings in which—

Figure 1 is a side elevation of a machine 55 constructed in accordance with this invention;

Fig. 2 is an inclined plan of the same looking in the direction of the arrow in Fig. 1 with parts broken away to show interior 60 construction;

Fig. 3 is a similar view of a portion of one of the run-ways on enlarged scale;

Fig. 4 is a side elevation on enlarged scale of the shaving arch and contiguous parts 65 with parts broken away to show interior construction;

Fig. 5 is a transverse sectional view on the line 5—5 of Fig. 4;

Fig. 6 is a similar sectional view on the 70 line 6—6 of Fig. 4;

Fig. 7 is a longitudinal sectional view on the line 7—7 of Fig. 6;

Fig. 8 is a sectional view on the line 8—8 of Fig. 2;

Fig. 9 is a still further enlarged sectional view of a portion of a plate showing how the tail is cut therefrom;

Fig. 10 is a longitudinal sectional view of one end of a finished plate showing how the 80 edges are finished; and Fig. 11 is a sectional view on the line 11—11 of Fig. 2.

These drawings show one form in which the invention can be embodied and in this form the machine is shown as comprising a 85 frame A having at one end thereof a platform B for receiving the cast plates from the hand casting box or other device in which they are made and holding them in convenient position for the removal of the matrix 90 by hand. This platform is shown as level for convenience in receiving and holding the semi-cylindrical plates and as provided with guides or tracks for directing the plates into proper position to enter the inclined run-way C down which the plates are adapted to move by gravity from the platform. Over the inclined run-way is located a shaving arch D and at the lower end of it is a cooling device E.

The machine is intended to be operated by power and for this purpose it is shown as provided with a motor F. The motor is supplied with power through any suitable

electrical connections. A starting pedal 10 is shown connected with a lever 11. The lever is connected by a link 12 with a circuit breaker 13 by which the operation of the 5 motor can be controlled.

A spring-pressed rod 14 normally tends to hold the lever down in position to break the circuit so that by stepping on the pedal the circuit can be made and the motor start- 10 ed. When this is down an arm or catch 15 connected with the pedal engages a locking lever or latch 16 and holds the parts in that position until automatically released as will be described hereinafter.

15 The motor is shown as connected through a flexible diaphragm coupling 17 with a shaft 18 mounted in bearings 19 suitably arranged on the frame work A. The shaft is shown as provided with a thrust collar 20 and with a worm 21 keyed on the shaft. This worm engages a worm wheel 22 keyed on a transverse shaft 23 which is provided with a worm 24 meshing with a worm wheel 25 keyed on a shaft 26. This is inclined at 25 the same angle as the run-way and is concentric with the shaving arch D. This shaft carries fixed thereon the usual shaving blade 27.

On the shaft 18 is mounted a spiral gear 30 arranged to mesh with and operate a spiral pinion 31 keyed on a shaft 32. Thus the shaft 32 rotates at a higher speed than the shaft 26. This shaft is mounted concentrically with the shaft 26 and projects into 35 it centrally into a chamber or gear pit 33 therein. The shaft 32 has a bearing at 34 in the concentric shaft 26. The shaft 32 carries in the gear pit 33 a bevel gear 35 meshing with a bevel gear 36 also in this chamber and mounted on a shaft 37. The latter is carried in a bearing 38 fixed on the shaft 26 at an angle to the axis thereof. The shaft 37 carries on its outer end a rotary cutter or saw 39 which is given a planetary motion 40 and a rapid rotation on its own axis while rotating with the shaving knife 27 about the axis of the shaft 26. It is to be observed that this rotary cutter is located inside the curved stereotype plate when it is in position in 45 the finishing arch for the purpose of being operated upon by the shaving knife therein. On account of being located in this place it cuts the tail from the plate in the manner indicated in detail in Fig. 9.

50 The cutter 39 forms a conical surface on the plate governed by the angle of the flat side of the cutter to the axis of the plate and it forms an interior conical surface on the tail of the plate. This reduces to a minimum the amount of metal removed, and makes a bevel on the plate edge, at the proper angle to fit the plate clamps on the printing machine.

55 Carried with the shaving blade 27 are shaving side tools 40 for trimming the sharp

edges of the plate at both ends which sometimes injure the hands of the workmen. This makes a groove lower than the type face and also removes the acute edge of the inner side, as shown in Fig. 10.

70

The inclined run-way is furnished near its upper end at both sides with edge cutting tools 41 for dressing the straight outside edges of the plate as it moves into the arch along the run-way from the platform. 75 One of these tools is pivoted on an axis 42 and a spring 43 is provided for normally holding it in cutting position. When the plate is forced over and up into the arch this permits the tool on one side to yield.

80

The shaft 26 is provided at a point, preferably just below the arch, with a three lobe cam 45 in the groove of which runs a stud or roller 46 on one arm of a three-arm cam lever 47. The other two arms of this lever 85 are connected by links 48 with a pair of oscillating members 49 at the sides of the arch and below the same. Each of these oscillating members is provided with a projection 52 engaging a pin 500 on an independently 90 pivoted stop 51. These stops are forced to turn inwardly by springs 50. The oscillating members 49 are adapted to be swung by the operation of the cam to force the stops from position under the arch and later to 95 move so as to allow the springs 50 to force the stops inwardly to stop the plate in proper position to be acted upon by the finishing devices which have been described.

100

Also mounted on a longitudinal shaft 53 along one side of the arch are lifting levers 54 normally pressed upwardly into the position shown in Fig. 5 by the spring 140 on the rod 14 and when the starting lever 11 is moved down to stop the machine the rod 14 105 on which the spring is located positively pulls these lifting levers 54 downwardly with it into the position shown in Fig. 6. In this position a plurality of movable sections 56 (along one side of the runway C and 110 under the arch) are projected out into position to support the plate in line with the runway. This is accomplished by pivoting these sections by means of arms 57 to the lifting levers and by supporting each section 115 56 on a horizontal ledge 58. A comparison of Figs. 5 and 6 will show clearly how these sections are forced outwardly into position to receive the plate when the lifting levers are pulled down.

120

At this time the cam lever 47 has acted to swing the stops 51 outwardly and has brought projections 59 to the level of a fixed ledge 60 on the bottom of the shaving arch and the movable sections 56 in their lowermost position for receiving an 125 outgoing plate. These parts support the plate and constitute a part of the run-way and when the machine is started the spring 140 forces the lifting levers up again into the position shown in Fig. 5, moves a new 130

plate up into its seat in the arch, and holds it there where it is ready to be acted upon by the rotary finishing device. The sections 56 and projections 59 receive the plate as it comes into the arch and support it when it is stopped by the stops 51. Then the projections 59 on one side act to lift one edge of the plate to the level of the fixed ledge 60. (Fig. 6). Then the lifting levers 54 take the other edge of the plate off the section 56, move it up into the arch and force it over on the ledge 60. (Fig. 5). When the cycle of operations is repeated, of course, the movable sections 56 and 59 are again brought into alignment with the rest of the run-way and the stops 51 which before projected inwardly are forced back out of the way. Thus each plate is allowed to slide down the run-way just after the rotary finishing devices leave it.

It has been stated that the lever 11 is provided with a hook or latch 15 on the end thereof which engages with a spring-seated locking lever 16 pivoted on the frame so that the plate will remain seated in the arch until released by the action of the three-arm cam lever 47 as has been explained. When this occurs an extended lobe of the cam causes the lever 47 to swing around to a position in which a projection 63 thereon engages with a projection 64 on the locking lever 16 forcing it to swing outwardly at the bottom about its pivot and releasing the starting pedal so as to allow the spring 14 to force it to its normal position in which the motor is disconnected from the power.

As has been stated, the plate is lowered from the arch on the inclined run-way by the reverse action of the lifting levers at this time and the swinging stops 51 are removed from the path of the plate so that it proceeds down the run-way by gravity to the cooling trough E. In order to prevent the tail from moving down the incline, a tail stop is provided consisting of a projection 68 extending up from the upper part of the frame and provided with a cross bar 69 of proper length to engage the inside of the concave conical end surface of the tail which is formed by the gate in casting. This stops the tail without interfering with the plate itself or the next plate, and leaves the tail where it can be removed from the machine by hand.

The cooling device is shown in the form of a concave trough 70 forming at one side a continuation of the inclined run-way C. The curve of this trough is described from a horizontal axis above the plate at right-angles to the path. The trough has on its interior surface and parallel therewith tracks 67 forming prolongations of the inclined run-way C. The object of this is to check the movement of the plate when delivered from the shaving arch to the cooling

trough. Each track is shown as having a notch 66 for allowing drainage therethrough.

An additional stopping means also is provided. This is shown in the form of a pivotedly mounted spring seated stop plate 71 fixed to an oscillatable shaft 81 above the delivery end of the cooling trough. Movable with this shaft and pivoted on the same axis as the plate is an arm 72 with which is pivotedly connected a reciprocable rod 73 having a spring 74 for forcing it up and thus yieldingly holding the stop in projected position ready to receive the impact of a plate. One of the spring rods 73 is provided with a water valve toe piece 75 for opening and closing a valve 76 in a water supply pipe 77. This is suitably connected with a hollow semi-cylindrical chamber 78 placed in the cooling trough parallel with the path of the plate. The top of this chamber is perforated throughout its length to permit the escape of the water in a spray against the entire inside surface of the semi-cylindrical plate. The trough is also provided with a partition or closure 79 so placed as to prevent the spray from escaping from the end of the plate toward the arch. The cooling trough is drained by means of a pipe 80 at the lowest point thereof.

Also swinging with the shaft 81 are a pair of arms 82. Each of these arms assisted by the plate 71 supports shafts 83 each having slidably mounted thereon a grooved roll 84 normally forced inwardly by springs 85. When a plate first comes into position to operate the stop plate its upper part engages the rolls and as it slides into a more nearly horizontal position it necessarily forces the rolls apart. The resistance of the springs 85 obviously tends to stop this action thus assisting in bringing the plate to rest.

The operation of the various parts of the machine is as follows:—A plate, as shown in dotted lines in Fig. 1, is placed on the platform B and moved over by hand onto the inclined runway. The operator then steps on the treadle 10 to start the machine. The locking lever or latch 16 then automatically holds the lever 11 in the operating position. When the plate has slid down the runway into the arch D the cams operate and cause the plate to be clamped in the arch by the movement of the lifting levers 54. The shafts 26 and 32 turn and perform the finishing operations above described. Then the lever 47 is operated by the cam to move the locking lever 16 out of engagement with the catch 15, which causes the machine to stop automatically due to the operation of the spring 140, and also the plate is lowered in the arch so that it is free to slide down into the cooling device. As its edge moves over the concave track 67 it is retarded and when its extreme edge engages the stop plate

71 the water is turned on and the plate cooled.

Although I have illustrated and described a single form of machine constituting a concrete embodiment of this invention, I am aware that the principle thereof can be carried out in many other forms without departing from the scope of the invention as expressed in the claims. Therefore, I do not wish to be limited to the particular mechanism shown and described, but what I do claim is:—

1. In a machine for trimming curved stereotype plates, the combination of means for supporting a plate means for severing the tail from a plate, and means located inside the supporting means for operating said severing means.

2. In a machine for finishing curved stereotype printing plates, the combination with a shaving arch adapted to receive a plate, of means located inside of a plate held in the arch for cutting the tail from the plate.

25. 3. In a machine for finishing curved stereotype printing plates, the combination with a shaving arch, of means for cutting the tails from the plates having its cutting edge extending outwardly from the inside thereof, and for simultaneously beveling the end edge of each plate by the tail cutting operation, said means being located inside the plate when held in the arch.

4. In a stereotype plate finishing machine, the combination with an arch adapted to receive a curved stereotype printing plate, of means located in position to come inside a portion of a plate when held in the arch for severing the tail therefrom.

40. 5. In a machine for finishing curved stereotype printing plates, the combination with a shaving arch, of means for cutting the tails from the plates, said means projecting outwardly from the inside of the arch.

45. 6. In a stereotype plate finishing machine, the combination of a semi-cylindrical arch for receiving a plate of corresponding shape, means for shaving the interior of a plate while held in the arch, and means located within a plate while in position in the arch for simultaneously cutting the tail from the plate.

55. 7. In a stereotype plate finishing machine, the combination of an arch for receiving a curved stereotype printing plate, a shaft concentric with the arch, a shaving knife on the shaft for shaving out the interior of the plate, and means on said shaft and located partly within the arch for cutting the tail from the plate while the interior of the plate is being shaved.

60. 8. In a machine for finishing stereotype printing plates, the combination of an arch for receiving a curved plate, a shaft in the

arch, a shaving knife on the shaft, a tail cutter mounted on said shaft to rotate therewith, and means carried by said shaft for rotating the tail cutter on its own axis while said shaft is rotating.

70. 9. In a stereotype plate finishing machine, the combination of an arch for receiving a curved stereotype plate, a longitudinal shaft, a shaft carried by the first named shaft at an inclination thereto and rotatable therewith, a tail cutter on the inclined shaft, and means for rotating said tail cutter on its own axis while the shaft is rotating.

10. In a stereotype plate finishing machine, the combination of an arch for receiving a curved stereotype plate, a shaft extending into the arch, a shaving knife on said shaft, a shaft carried by the first named shaft at an inclination thereto and rotatable therewith, a tail cutting saw on the inclined shaft and making an angle with the surface of the plate, and means for rotating said tail cutter on its own axis while the shaft is rotating, whereby the tail will be severed from the plate and the edge of the plate beveled.

11. In a stereotype plate finishing machine, the combination of an arch for receiving a curved stereotype plate, a shaft extending under the arch, a shaving knife on said shaft, a shaft carried by the first named shaft at an inclination thereto and rotatable therewith, a tail cutter on the inclined shaft and making an angle with the surface of the plate, and means for rotating said tail cutter on its own axis while the shaft is rotating, and a side cutter movable with the shaving knife for finishing the edge of the plate.

105. 12. In a stereotype plate finishing machine, the combination of a hollow shaft, a second shaft extending into the hollow shaft and supported at one end thereof, means for rotating the hollow shaft, means connected therewith for rotating the inner shaft at a higher speed, a tail cutter carried by the hollow shaft, and means within the hollow shaft for rotating the tail cutter from the inner shaft.

115. 13. In a stereotype plate finishing machine, the combination of a shaving shaft having a central longitudinal passage therein, a shaft mounted in said passage, means for rotating said shafts at different speeds, a third shaft supported at an inclination on the first shaft and having a cutting tool thereon, and means for transmitting a rotary motion from the second to the third shaft.

120. 14. In a stereotype plate finishing machine, the combination of rotary means for cutting the tail from a curved plate, means following the tail cutter for shaving the interior of the plate, and means following the shaving means for trimming the edge operated upon by the tail cutter.

15. In a stereotype plate finishing machine, the combination with a run-way, and an arch located therealong for receiving a curved plate therein, of a ledge along one side of the arch and movable sections along the other side of the arch constituting part of said run-way for receiving and guiding the plate as it moves along the run-way, and means for forcing the edge of the plate resting on said movable sections up into the arch and simultaneously withdrawing the movable sections.

16. In a stereotype plate finishing machine, the combination with a run-way and an arch located therealong having a movable section constituting a part of said run-way and located along one side of the arch below the same, of a plate lifting lever adjacent to said movable section, means for moving said lever to raise the edge of the plate in the arch, and means for simultaneously withdrawing the movable section.

17. In a stereotype plate finishing machine, the combination of an arch, a lifting lever adapted to engage the edge of a plate under the arch and lift it into the arch, a run-way adjacent to the arch comprising a movable section pivotally connected with the lifting lever, and a ledge for supporting said movable section.

18. In a stereotype plate finishing machine, the combination of an arch, a lifting lever adapted to engage the edge of a plate under the arch and lift it into the arch, a movable section pivotally connected with the lifting lever, and a ledge for supporting said movable section, whereby when the lifting lever is raised the movable section will be withdrawn from operative position along said arch and whereby when the lifting lever is withdrawn the movable section will be projected into the path of the plate.

19. In a stereotype plate finishing machine, the combination of an arch, a lifting lever adapted to engage the edge of a plate under the arch and lift it into the arch, a run-way adjacent to the arch comprising a movable section pivotally connected with the lifting lever, a ledge for supporting said movable section, a stationary ledge on the other side of the arch, and a movable member mounted adjacent to said ledge and beyond the edge thereof for assisting in supporting that edge of the plate when it is moved into the arch.

20. In a stereotype plate finishing machine, the combination of an arch, a lifting lever adapted to engage the edge of a plate under the arch and lift it into the arch, a movable section, a ledge for supporting said movable section, a stationary ledge on the other side of the arch, a movable member mounted adjacent to said ledge and beyond the edge thereof for assisting in supporting that edge of the plate when it is moved into

the arch, and means whereby when the lifting lever is operated to move the plate positively into the arch said member will be withdrawn.

21. In a stereotype plate finishing machine, the combination with an arch and a run-way extending therealong, of a fixed ledge at one edge of the arch adapted to support one edge of the plate when the plate is positioned therein, an oscillatable member having a portion which in one position constitutes a continuation of said ledge for supporting the plate when it is moved into the arch, means for forcing the opposite edge of the plate up into the arch and thus moving the plate back on the ledge, and means for simultaneously withdrawing said projection.

22. In a stereotype plate finishing machine, the combination with an arch, of a fixed ledge at one edge thereof for supporting the edge of a printing plate, and an oscillatable member adjacent to said ledge having a projection adapted in one position to form a continuation of the ledge to assist in supporting the plate.

23. A stereotype plate finishing machine comprising a run-way consisting of a fixed ledge and a movable projection adapted to move into a position flush with the upper surface of the ledge to assist in supporting the edge of a plate to be finished.

24. In a stereotype plate finishing machine, the combination of a shaft, finishing devices rotatable therewith, a cam rotated by said shaft, a lever operated by the cam, means controlled by said lever for forcing a plate into position within the arch ready to be finished and for stopping the application of power to the shaft at a predetermined point, a run-way for supporting the plates, and means operated by said cam for moving the sections of said run-way into position to receive the plate from the arch.

25. In a stereotype plate finishing machine, the combination of an arch for receiving the plates to be finished, a run-way extending under the arch, a pair of stops adapted to extend into the path of a plate to register the plate with the arch, and means for simultaneously withdrawing said stops and forcing the plate positively to a seat in the arch.

26. In a stereotype plate finishing machine, the combination of a run way section, a lifting lever for a plate, a fixed ledge, a projection adapted to come into position flush with said ledge, a stop, yielding means for moving said stop and lifting lever into operative position, and positive means for withdrawing them to inoperative position.

27. In a stereotype plate finishing machine, the combination of a movable lifting lever for a plate, a movable stop, a single means for moving each of said movable members into operative position, and inde-

- pendent means for withdrawing them to inoperative position.
28. In a stereotype plate finishing machine, the combination of a pivoted lifting lever for a plate, a pivoted stop, yielding means for moving each of said pivoted members into operative position, and positive means for withdrawing them to inoperative position. 70
- 10 29. In a stereotype plate finishing machine, the combination of an arch for receiving the plates to be finished, of a run-way extending under the arch, a pair of stops adapted to extend into the path of a plate to register the plate with the arch, a cam, a cam lever operated thereby, a pair of oscillatable members connected with the cam lever and oscillated thereby in opposite directions simultaneously, a support for the printing plate on one of said members, a lifting lever for forcing the plate to a seat in the arch, and means connected with the other of said members for withdrawing the lifting lever when in operative position. 75
- 15 30. In a stereotype plate finishing machine, the combination of a shaft, finishing devices rotatable therewith, a cam rotated by said shaft, a lever operated by the cam, means controlled by said lever for forcing a plate into position within the arch ready to be finished, a run-way for supporting the plates, means operated by said cam for moving a portion of said run-way into position to receive the plate from the arch, stops 80 for the plate and means operated by said cam for controlling the motion of the stops into and out of operative position. 85
- 20 31. In a stereotype plate finishing machine, the combination with an arch, and an inclined run-way for feeding a plate by gravity through the arch, said run-way having movable sections, of stops for engaging the forward edge of the plate and holding it on the run-way, and means whereby when 90 said movable sections are moved out of alignment with the run-way toward the arch, said stops will be withdrawn from the path of the plate. 95
- 25 32. In a stereotype plate finishing machine, the combination with an arch, and an inclined run-way for feeding a plate by gravity through the arch, said run-way having movable sections, of stops for engaging the forward edge of the plate and holding it on the run-way, and means for moving 100 said movable sections toward the arch for clamping a plate therein and withdrawing said stops positively from the path of the plate. 105
- 30 33. In a stereotype plate finishing machine, the combination with an arch, a run-way extending thereunder for guiding plates therethrough, said run-way having a series of movable sections, a pair of pivoted stops at the discharge end of the arch for 110
- 35 engaging the edge of the plate and preventing its discharge from the arch, means for moving said sections to force the plate up into the arch to be shaved, and means operated by the last named means for withdrawing the stops from operative position. 115
- 40 34. In a stereotype plate finishing machine, the combination of a shaft, finishing devices rotatable therewith, a cam rotated by said shaft, a lever operated by the cam, means controlled by said lever for forcing a plate into position within the arch ready to be finished and for stopping the application of power to the shaft at a predetermined point. 120
- 45 35. In a stereotype plate finishing machine, the combination of an arch for receiving a plate to be finished, a shaving blade in the arch, a motor for operating the shaving blade, means for disconnecting the motor from the power, means for holding said disconnecting means inoperative, and means operated by said shaft for releasing the holding means at a predetermined point. 125
- 50 36. In a printing plate finishing machine, the combination of a rotary shaving blade, a motor for rotating it, a switch for connecting the motor with power and disconnecting it therefrom, yielding means for normally holding the switch in a position to disconnect the motor from the power, a latch for holding the switch in operative position against the action of said yielding means, and means rotatable with the shaving knife for releasing said latch. 130
- 55 37. In a printing plate finishing machine, the combination of a rotary shaving blade, a motor for rotating it, a switch for connecting the motor with power and disconnecting it therefrom, yielding means for normally holding the switch in a position to disconnect the motor from the power, a latch for holding the switch in operative position against the action of said yielding means, a pivoted cam lever, a cam rotatable with the shaving knife, and means operated by said cam for swinging the cam lever about its pivot and disconnecting the latch from the switch. 135
- 60 38. In a machine of the character described, the combination of an inclined run-way for the plates, means for cutting the tail from a plate while on the run-way, and means on the run-way for arresting the tail thereon. 140
- 65 39. A machine of the character described having an inclined run-way and means near the upper end thereof for stopping the severed tail of a curved stereotype printing plate. 145
- 70 40. A machine of the character described comprising a run-way for curved stereotype plates and a tail stop consisting of a transverse rod adapted to engage the inner conical surface of the tail. 150

41. In a stereotype plate finishing machine, the combination with an inclined run-way down which the plates are adapted to be fed, a horizontal table at the upper end 5 of said run-way for receiving the plates, stationary cutters in position to trim the edges of the plates as they pass down the run-way, means for finishing the plates located adjacent to said run-way, and a receiving table 10 at the bottom of the run-way.
42. In a stereotype plate finishing machine, the combination with an inclined run-way down which the plates are adapted to be fed, a horizontal table at the upper end 15 of said run-way for receiving the plates, stationary cutters in position to trim the edges of the plates as they pass down the run-way, means for finishing the plates located adjacent to said run-way, and a receiving table 20 at the bottom of the run-way having a surface for receiving the end of the plate curved on an arc drawn from an axis above the lower end of the run-way and transverse to the direction of motion of the plates.
43. In a stereotype plate finishing machine, the combination of an inclined run-way, and a receiving table at the bottom thereof of longitudinally concave form constituting a continuation of the run-way.
44. A receiving table for a stereotype plate having a longitudinally concave upper surface.
45. In a stereotype plate finishing machine, the combination of an inclined run-way, a receiving table at the bottom thereof of longitudinally curved form constituting a continuation of the run-way, and a spring-pressed stop at the end of said receiving table for limiting the motion of the plates 40 thereon.
46. In a stereotype plate finishing machine, the combination of an inclined run-way, a receiving table at the bottom thereof of concave form constituting a continuation 45 of the run-way, a spring-pressed stop at the end of said receiving table for limiting the motion of the plates and means connected with said spring-pressed stop for turning on a cooling fluid to cool the plates when 50 the stop is actuated by a plate.
47. In a machine of the character described, the combination of a trough or receiving table for a plate having a concave form adapted for checking the motion of the plate when introduced therein, and resilient means for stopping the plate.
48. In a device of the character described, the combination of a trough shaped concave receiving table for a plate, a pivoted stop 60 at the end thereof, means for yieldingly holding the stop in projected position, and means connected with said stop for turning on a cooling fluid to cool the plate in the trough.
49. In a stereotype plate finishing ma-
- chine, the combination of a receiving table, a spring-pressed stop at the end of said receiving table for limiting the motion of the plates, and means connected with said spring-pressed stop for turning on a cooling fluid to cool the plates when the stop is actuated by a plate. 70
50. In a machine of the character described, the combination of a trough or receiving table for a plate, a pivoted plate at 75 the end of the trough for engaging the advancing end of the plate and stopping the plate, and means operated by the pivoted plate for turning on a cooling fluid to cool the plate. 80
51. In a machine of the character described, the combination of a trough for receiving a concave plate, means for applying a cooling fluid to the inside of the plate when in said trough, a fixed closure at one end of 85 the trough for preventing the discharge of the cooling fluid, and a movable spring-pressed plate at the other end of the trough for stopping the plate and preventing the discharge of cooling fluid at that end. 90
52. In a machine of the character described, the combination of a trough for receiving a concave plate, means for applying a cooling fluid to the inside of the plate when in said trough, and a movable spring-pressed plate at the end of the trough for 95 stopping the plate and preventing the discharge of cooling fluid at that end.
53. In a device for finishing stereotype printing plates the combination with a receiving table for the plates of a movable stop, grooved rollers on the stop movable out and in thereon in position to receive the edges of the plate, and means for resisting the outward motion of the rollers. 100 105
54. In a device for finishing stereotype printing plates the combination with a receiving table for the plates, having a longitudinally concave surface, and an inclined run-way leading thereto, of a movable stop, 110 grooved rollers on the stop movable out and in thereon in position to receive the edges of the plate, and means for resisting the outward motion of the rollers.
55. In a stereotype plate finishing machine, the combination of a concave table for receiving the plates from the finishing mechanism means for directly resisting the motion of the plate along the table, and means for engaging the advancing front 120 curved edges of the plate and means cooperating with said engaging means for resisting the rise of the end of the plate at the end of the concave table.
56. In a device of the character described, 125 the combination of a pivoted stop plate, a shaft carried thereby, a grooved roll slidable along the shaft and means for resisting the outward motion of the roll along the shaft.
57. In a stereotype plate finishing ma-

- chine, the combination of an arch, edge trimming tools, and means for allowing one of the tools to yield to permit the plate to be moved into the arch.
- 5 58. In a stereotype plate conveying system, the combination of an inclined run-way, and a receiving section at the bottom thereof, of substantially longitudinally concave form constituting a continuation of the run-way.
- 10 59. In a machine for finishing curved stereotype printing plates, the combination of means for holding a plate, a shaving blade for shaving out the interior of the plate, a saw rotatable with said shaving blade for cutting the tail from the plate, and means for giving the saw a planetary motion.
- 15 60. In a machine for finishing curved stereotype printing plates, the combination of a knife for shaving out the interior of the plate, a saw for beveling the end edge of the plate, and means for giving the saw a planetary motion.
- 20
61. In a machine for finishing curved stereotype printing plates, the combination of a knife for shaving out the interior of the plate, a saw located inside the plate for beveling the end edge of the plate, and means for giving the saw a planetary motion around the inside of the plate at the end thereof. 25
62. In a machine for finishing curved stereotype printing plates, the combination of a shaving blade for shaving out the interior of the plate, a saw located inside the plate rotatable with said shaving blade for cutting the tail from the plate, and means for giving the saw a planetary motion around the inside of the plate at the end thereof. 30
